METHOD OF TUFTING MATTRESSES

Wilfred B. Mathewson, North Weymouth, Mass., assignor to United Mattress Machinery Company, Boston, Mass., a Corporation of Maine

Application October 9, 1931. Serial No. 567,782

3 Claims. (Cl. 112—3)

This invention relates to a method of tufting mattresses and it has for one of its objects to provide an improved method which is especially applicable to the tufting of so-called "inner spring" mattresses although the invention is equally applicable to the tufting of any mattress.

In carrying out the invention the tufting needle is inserted through the mattress while the latter is in a noncompressed condition thereby carrying through the mattress a single end of tufting cord. A tufting knot with the usual tuft therein is then formed in the end of the cord which has been passed through the mattress, all this being accomplished while the mattress is in a normal uncompressed condition.

The needle is then withdrawn from the mattress and simultaneously the mattress is compressed to the desired extent at the point where the needle was inserted or where the tuft is to be made thereby drawing the previously-formed tufting knot firmly against the side of the mattress.

After the needle has been completely withdrawn from the mattress a second tufting knot with its corresponding tuft is formed in the cord on the opposite side of the mattress and the tufting cord is severed thereby completing the tufting operation.

As applied to a so-called "inner spring" mattress this method has the advantage that since the needle is inserted through the mattress before the latter is compressed and while the inner springs are still in their expanded condition the latter are free to give either in the direction of the length of the spring or transversely thereto in case the needle strikes any coil of the spring during the penetrating thrust. This ability of the spring to yield freely in case it is engaged by the needle during the penetrating thrust allows the needle to readily slip by the spring without causing any damage either to the spring or to the needle such as would be likely to occur if the mattress and inner springs were compressed before the needle was thrust through the mattress and during the penetrating thrust of the needle which engaged the compressed spring.

In order to give an understanding of the invention I have illustrated in the drawings one way of practising the invention which will now be described after which the novel features will be pointed out in the appended claims.

Fig. 1 is a side view of a mattress-tufting machine by which my improved method may be carried out;

Figs. 2, 3, 4, 5, 6 and 7 show various steps in the process of tufting a mattress in accordance with the present invention;

In the drawings 1 indicates a mattress to be

tufted and it is illustrated as an inner spring mattress, that is, one having a plurality of springs 2 within the body of the mattress, said spring being covered on each side of the mattress by a suitable padding 3 and the mattress having, of course, the usual ticking 4.

In carrying out my improved method I first thrust a tufting needle 5 through the mattress at the point where any tufting knot is to be applied and while the mattress is in an uncompressed condition and the springs 2 are in their normal expanded condition.

The needle, of course, carries the usual tufting cord 6 so that during this thrust of the needle through the mattress a length of tufting cord will be carried therethrough thereby to provide a portion 7 of the cord which projects beyond the face 8 of the mattress from which the needle emerges. A tufting knot is then tied in this projecting portion 7 of cord and a suitable length of tufting yarn inserted in the knot in usual way thereby to form the tuft 9 as shown in Fig. 3.

After the tuft 9 has been formed the needle is withdrawn from the mattress and at the same time the mattress is compressed to the desired extent at the tufting point as shown in Fig. 4.

During the withdrawing of the needle the tuft 9 will be pulled firmly against the face 8 of the mattress and when the needle has been completely withdrawn from the mattress as shown in Fig. 5 a single length 11 of the tufting cord 6 will extend through the mattress. Another tufting knot and tuft 12 is then formed in the tufting cord 6 at the face 13 of the mattress and the tufting cord is cut. The pressure on the face 8 of the mattress is then relieved and the tufting operation is completed and as shown in Fig. 7 there will be a single length of tufting cord 11 extending through the mattress and two tufts 9 and 12 at the ends of the length 11 of cord and on the opposite faces of the mattress.

There is a distinct advantage in this improved method when applied to the tufting of inner spring mattresses for since the tufting needle 5 is inserted through the mattress while the latter is in a non-compressed or normal condition with the springs 2 in their expanded condition the individual turns of any spring are free to shift or yield both in the direction of the length of the axis and in a direction transverse thereto in case it is engaged by the needle during the penetrating thrust of the latter. Where the mattress is compressed before the needle makes its penetrating thrust and is under compression during such thrust there is grave danger that if in thrusting the needle through the compressed mattress it engages a compressed spring, either the spring or the needle will be

come broken or damaged. Where the spring is compressed the coils are locked in position and cannot readily yield in case they are engaged by the needle but where the spring is non-compressed and is in its expanded condition then any turn of the spring is free to shift if it should be engaged by the needle thereby allowing the needle to pass the spring without either injuring the spring or the needle.

10 I have shown more or less diagrammatically in the drawings, a machine adapted to carry out my improved method.

Referring to Fig. 1, 14 indicates generally a mattress tufting machine which is provided with a bed or carriage 15 on which the mattress 1 to be tufted is placed. This machine is shown as having the overhanging arm 16 which carries at its end an upper knotting device 17 of some suitable type and also a vertically-movable presser foot 18 by which the mattress is compressed. The machine is also provided with a lower knotting device 19 of some suitable type, the two knotting devices being operated by two shafts 20 and 21 which are connected to work in proper timed relation through the medium of a connecting shaft 22. The needle 5 operates from the bottom and is thrust upwardly through the mattress. Said needle is carried by a needle bar or needle carrier 23 which is mounted for vertical reciprocation in suitable guides 24 carried by the base of the frame. Said needle carrier 23 is actuated by a lever 25 pivoted to the frame at 26, said lever being connected to the carrier through a link 27 and being actuated by a cam groove 28 formed in a cam member 29. This cam member gives the needle its appropriate reciprocating movement.

The presser foot is mounted for vertical movement to enable it to perform the mattress-compressing operation. Said presser foot is shown as provided with a stem 30 in the form of a rack which engages a pinion 31 and said pinion also meshes with and is actuated by a horizontally-extending rack 32 which is connected by a link 33 to an elbow lever 34 pivoted to the frame at 35. One arm of this elbow lever is connected by a link 36 to a lever 37 pivoted to the frame at 38 and at the pivotal connection between the link 36 and arm 37 is a follower 39 operating in a cam groove 40 formed in the cam element 29.

In the operation of the machine the cam path 28 first actuates the lever 25 to cause the needle 5 to penetrate the mattress, this occurring while the presser foot 18 is still in its raised position and while the mattress is still uncompressed. When the needle has completed its penetrating thrust as shown in Fig. 1 the knotter 17 operates to form the knot or tuft 9 in the tufting cord 6. When the knotter 17 has completed its operation the cam path 28 operates to withdraw the needle as shown in Figs. 3 and 4 and at the same time the cam path 40 actuates the elbow lever 34 to depress the presser foot 18 and compress the mattress, this compressing of the mattress occurring simultaneously with the withdrawal of the needle. The cam path 40 will hold the presser foot in its lowered position until the needle 5 is completely withdrawn from the mattress and until the lower knotting device 19 has formed the lower tuft 12 and the tufting cord has been cut. The presser foot is then raised to its normal position thus completing the

cycle and the machine is then ready to repeat the operations in making another tuft.

Inasmuch as the present invention relates to the method I have not thought it necessary to describe the machine in detail but have simply illustrated a tufting machine sufficiently to enable the process to be understood.

An important feature of the invention is that the needle is inserted through the mattress before the latter is compressed and while the inner springs are expanded so that the individual turns of the spring are in condition to readily flex or yield in case they are engaged by the needle during its penetrating thrust thereby to permit such thrust to be made without danger of breaking the spring or needle. In accordance with this invention the necessary compression of the mattress at the tufting point takes place after the needle has been inserted through the mattress and preferably after the tuft on the upper face of the mattress has been formed and while the needle is being withdrawn.

I claim.

1. The method of tufting mattresses which consists in mechanically inserting a threaded needle through the mattress while the latter is uncompressed thereby to carry a tufting cord through the mattress, tying a tuft to the end of the cord which has been thus carried through the mattress, withdrawing the needle from the mattress and simultaneously compressing the mattress at the point where the tuft is being made, and while the mattress still remains compressed forming a second tufting knot in said cord on the opposite side of the mattress from that on which the first knot was made.

2. The method of tufting mattresses which consists in inserting through the mattress while the latter is uncompressed a needle threaded with a single tufting cord thereby to carry a single length of tufting cord through the mattress from the side thereof into which the needle entered to the side from which the point of the needle emerged during its penetrating thrust, tying a tuft to the end of the single tufting cord which has thus been carried through the mattress on the face of the mattress through which the point of the needle emerged, withdrawing the needle from the mattress while the cord is still threaded through the eye thereof thereby leaving a single length of tufting cord extending from the tuft through the mattress, compressing the mattress at the point where the cord is located without increasing the tension of the cord, and while the mattress remains compressed severing the cord between the mattress and the needle and tying a second tuft to the cord on the face of the mattress into which the needle was inserted.

3. The method of tufting mattresses which consists in inserting a single length of tufting cord through the mattress while the latter is in an uncompressed condition so that a free end of the cord is exposed on one face of the mattress, tying a tuft to said free end, compressing the mattress at the point where the cord has been inserted, drawing the single cord taut to bring said tuft against said face of the mattress, and while the mattress is compressed tying a tuft to the cord in close adjacency to the other face of the mattress.

WILFRED B. MATHEWSON.
